HIS ATTORNEYS

UNITED STATES PATENT OFFICE.

FRANK B. ALLEN, OF CLEVELAND, OHIO. ASSIGNOR, BY MESNE ASSIGNMENTS, TO
FRANK H. DUNBAR.

ASH-HOPPER CONSTRUCTION.

Application filed March 21, 1921. Serial No. 454,322.

To all whom it may concern:

Be it known that I, FRANK B. ALLEN, a citizen of the United States, residing in Cleveland, in the county of Cuyahoga and

5 State of Ohio, have invented certain new and useful Improvements in Ash-Hopper Constructions; and I do hereby declare the following to be a full, clear, concise, and exact description of the invention, such as 10 will enable others skilled in the art to which it appertains to make and use the same.

My invention relates to hoppers and gates therefor together with mechanism for operating the doors of such gates.

15 Up to the present time, the operators of large power plants have been seriously affected by defective ash controlling apparatus. The larger the plant the more serious and aggravated have the troubles arising from this source of the plant become.

Almost any mediocre means for handling the ash of a small plant will give reasonable satisfaction but as the size of the plant is increased, and with the coming of automatic 25 stokers and forced drafts, the matter of handling the large volume of ash in a super-heated condition as a result of the forced draft, together with the necessity of using water for cooling the ashes, the matter has 30 become more and more serious and the deficiency of the old type of equipment has become more and more noted and accentuated. The problem that confronts the installer and manufacturer of this type of 35 equipment is not only a question of effectiveness in mechanism but likewise a question of cost of construction, and up to the present time the solution of these two questions has not been obtained as it has in the 40 present invention.

Until very recently, a boiler containing five thousand square feet of heating surface, for example, was called a 500 H. P. boiler. Today the same boiler is operated to produce 45 1000 to 1500 or even 2000 boiler H. P. To obtain this result, resort has been had to force draft. The type of ashes produced under these circumstances is more difficult to handle than was formerly the case. This 50 is further aggravated by the increasing tendency to use coals of lower grade, and is

further aggravated by the fact that whereas formerly the size of a boiler seldom exceeded 500 H. P. now they are practically always between 1400 and 2500 H. P.

55 The net result of all of these new conditions, is that whereas formerly in a large installation, about 3½ tons of clean, disintegrated ashes had to be removed from a single boiler daily, today from 20 to 50 tons 60 of clinkered ash, highly heated, must be handled from each boiler. When it is further considered that in a modern station there are provided from ten to twenty such 65 boilers, the difficulty of handling the ash becomes apparent.

In meeting these conditions and solving the problems created thereby, the inventor has produced the invention described herein, among the objects of which are the following:

To provide a frame for the gate which is directly attached to the steel ribs of the hopper.

To provide means cooperating with the gate frame and door for collecting liquid passing through the hopper and conducting the same to a suitable drain thereby maintaining the floor beneath the gate and hopper substantially dry.

80 To provide other details of improvement tending to increase the efficiency and serviceability of devices of the above character.

To accomplish the foregoing and other useful ends, my invention consists of means 85 hereinafter more fully set forth and claimed.

Referring more particularly to the accompanying drawings in which I have illustrated a structure embodying my invention:

Fig. 1 is a top plan view of a gate comprising a gate frame, door and supporting and operating means for a door for a single hopper opening.

Fig. 2 is a side view, partly in section, taken on line 2—2 of Fig. 1.

Fig. 3 is an end view, partly in section and partly in elevation, of the device shown in Fig. 1.

Fig. 4 is a perspective view, from below, of two hoppers constructed in accordance 100 with my invention.

Fig. 5 is a sectional view taken through

the frame of Figs. 1 and 2 showing in section the wall 17 and the stationary trough 25 of Fig. 2.

Referring first to Fig. 4, 1 indicates as an 5 entirety a hopper which may be employed with a coal burning furnace of the automatic stoker type (not shown) and which is so positioned with respect to such a furnace as to receive ashes discharged therefrom. 10 2 designates certain metal frame work members on which a floor (not shown) may be supported around the furnace.

Hopper 1 which is suspended from members 2 is preferably composed of a plurality of spaced ribs 3 suspended from members 2 and carrying at their lower ends a gate frame 4. The upright walls of the hopper are formed by metal plates 5 secured to the inner side of ribs 3, as by bolts 20 or otherwise. Flanges 6 integral with plates 5, serve to support in part the refractory lining members 7. 8 designates the opening at the top of the hopper through which ashes from the furnace may be discharged 25 into the hopper.

The bottom wall of hopper 1 is formed by a gate frame 4 suspended from framework 2 by ribs 3 as described, and having an enlarged substantially rectangular centrally 30 arranged opening 10 therethrough, and a door 11 movably mounted on the frame 4 to close opening 10. Supporting means in the form of parallel rails 12, which form a track for the wheels 13 of door 11, permit 35 the door to be moved relative to the frame and to opening 10. Material held in the hopper when door 11 is in closed position with respect to opening 10 may be discharged through this opening when the 40 door is suitably moved.

To the bottom of door 11 is attached a bracket 14 which carries a connecting rod 15 operating in a cylinder 16 and having a piston (not shown) connected thereto 45 within the cylinder. Movement of the piston serves to move the door 11 into open or closed position with respect to the opening 10 and frame 4.

In this figure cylinder 16 is located between the adjacent hoppers 1 and suspended below rails 12. It is provided with two pistons (not shown), to actuate the adjacent doors of these hoppers.

It will be seen that my improved hopper 55 construction may be considered as a skeleton structure since it comprises the overhead supporting members 2, the spaced ribs 3, the gate frame 4, with the wall plates secured to the ribs and the door movably 60 mounted in the frame.

Referring now to Figs. 1, 2 and 3 where I have shown a slightly modified form of door actuating mechanism and certain elements additional to the door as shown in 65 Fig. 4, the gate frame 4 is formed with a

depending flange 17 at one end and walls 18 spaced vertically beneath the opposite sides 19 of member 4 but connected thereto at intervals by spaced ties 20, all of which is clearly shown in Figs. 2, 3 and 4.

21 indicates parallel members secured at one end to the frame 4 and suitably supported at the opposite ends to serve as rails comprising a track for the wheels of a 75 door 11.

Cross members 22 unite the rails 21 at some distance from the frame 4 and carry a cylinder 23 provided with a piston (not shown) to which is attached a connecting rod 24, this rod being attached at its opposite end to door 11. Fluid pressure means may be suitably connected to cylinder 23 to operate the piston back and forth therein, these means however not being shown herein.

Door 11 which is adapted to close the opening 10 through frame 4 is provided with wheels 13 arranged to run on rails 21 when the door is being opened with respect to this opening, certain of the wheels being 90 arranged to run on the walls 18 of member 4 as will be evident by reference to Figs. 1 and 2.

In the actual operation of furnaces of the type described herein ashes in the hopper are often sprayed with water or other cooling liquid to cool the same, and any water in excess of the amount which will be absorbed by the ashes flows to the bottom of the hopper and leaks out around the door 95 unless special provision is made for collecting it. Means for collecting such water is indicated in Figs. 2 and 3 where 25 indicates a stationary trough secured to the front end of frame 4 and suspended beneath the depending end wall 17.

A pipe 26 serves to conduct water from trough 25 to a suitable drain (not shown). Along the opposite sides and rear end of door 11, that is the end nearer cylinder 23, I secure communicating side water troughs 110 27 and end trough 28, the troughs being preferably suspended along the periphery of the door, so that water running over the edge thereof will flow down into the troughs and empty at the front end of the door into trough 25. Flanges 29, which depend from the walls 19 of the frames 4 along the sides of and close to openings 10, serve as baffles to deflect liquid passing over the top of the door with some velocity, the liquid being deflected thereby into the underlying troughs 27.

Figs. 2 and 3 indicate clearly the construction and location of troughs 27 and 125 28 and the means for attaching them to the door. The forward ends of the side troughs 27 along the longitudinal sides of the door 11 are extended sufficiently so that when the door is in closed position with respect to 130

openings 10 of frame 4 the ends of the troughs 27 will project over the trough 25 so that liquid will be discharged therefrom into trough 25.

Having thus described my invention as embodied in one form of practical device, what I desire to secure by Letters Patent is defined in the claims, it being understood that various changes not involving invention which may occur to those skilled in the art may be made without departing from the spirit and the scope of my invention.

What I claim is:—

1. A receptacle for comminuted materials having a discharge outlet and a movable closure therefor, means for receiving the liquid draining from the receptacle when said outlet is closed, and means connecting the closure and liquid receiving means for moving the liquid receiving means when the closure is moved.

2. A receptacle for comminuted materials having a discharge outlet and a closure therefor, a trough disposed to receive liquid and comminuted material passing through the outlet when the closure is in closed position, and means connecting the closure and the trough for moving the trough out of liquid and comminuted material receiving position when the closure is opened.

3. A door for a hopper having a bottom opening, provided with liquid collecting and discharging means along one side thereof.

4. A door for a hopper having a bottom opening, provided with liquid collecting and discharging troughs below and along a plurality of sides thereof.

5. A gate for a hopper having a bottom opening, comprising a door having liquid collecting and discharging troughs along a plurality of sides thereof, and a stationary trough adapted to receive liquid from the first said troughs.

6. A gate for a hopper having an opening, comprising a movable door, a water collecting trough movable with said door, and a stationary trough overlapped by said door and adapted to receive liquid therefrom when the latter is in closed position with respect to said opening.

7. A gate for a hopper having an opening, comprising a movable door for the opening, a water collecting trough suspended from the said door, a stationary trough adapted to receive water from the trough in the door when the door is in closed position with respect to said opening, and means for moving the door into open or closed position with respect to the said opening.

8. A gate construction, for a hopper having a discharge opening, comprising a horizontally movable closure for the said open-

ing, a stationary liquid receiving trough, and a wall disposed adjacent to the trough and extending above and below the top of the said closure, the said wall being adapted to intercept liquid passing from the top of the closure when the latter is in closed position and to deflect such liquid into the said stationary trough.

9. A horizontally movable door, for a hopper having a bottom opening, provided with means for collecting liquid passing through the said opening and discharging the same at one end of the door.

10. A combination of a hopper provided with a bottom discharge opening; a gate under the hopper; means for moving the gate into and out of closed position; and gutters on the gate for carrying away the water escaping from the material in the hopper.

11. A receptacle for comminuted materials having a discharge outlet and a movable closure therefor, a movable trough capable of movement into and out of position to receive liquid passing through the said outlet, and means connecting the trough and closure for moving the trough into position to receive liquid passing through the said outlet when the closure is closed.

12. A gate construction for an ash hopper having a bottom opening, comprising a stationary member surrounding said opening and having downwardly extending portions, a door mounted for movement into open and closed position in respect to said opening, said door being adapted to cooperate with said stationary member when in closed position to substantially prevent the escape of ashes between the door and stationary member, said door having means for collecting liquid and discharging the same at one end, said means including upwardly extending portions on the door which extend above the bottom of said downwardly extending portions.

13. A gate construction for a hopper having a bottom opening, comprising a stationary member adapted to surround the said opening, a door for the said opening, and means for collecting liquid discharged between the said stationary member and door comprising a downwardly extending wall on the stationary member, an upwardly extending wall on the door in telescoping relation therewith, and a trough on the door in fluid-receiving position with respect to the said downwardly and upwardly extending walls.

14. A gate construction for a hopper having a bottom opening, comprising a stationary member adapted to surround the said opening, a door for the said opening, and means for collecting liquid discharged between the said stationary member and door

comprising a downwardly extending wall on the stationary member, an upwardly extending wall on the door in telescoping relation therewith, a trough on the door in fluid-receiving position with respect to the said downwardly and upwardly extending walls, and a stationary trough adapted to

receive liquid discharged from the door when same is in closed position with respect to the said opening.

10

In witness whereof, I have hereunto signed my name this 17th day of March, 1921.

FRANK B. ALLEN.
